STUDY CARREL

Chester J. Barecki, Grand Rapids, Mich., assignor to
American Seating Company, Grand Rapids, Mich., a
corporation of New Jersey

Filed Mar. 5, 1965, Ser. No. 84,106

Term of patent 14 years

(Cl. D33—11)

FIGURE 1 is a perspective view of a study carrel showing my new design;

FIGURE 2 is a top plan view thereof; and

FIGURE 3 is a side perspective view thereof.

The dominant features of my design reside in those portions shown in full lines on the drawing.

I claim:

The ornamental design for a study carrel, as shown and described.
